UNITED STATES PATENT OFFICE

2,203,079

CONVEYER TRANSFER AND SEAL MEANS

Austin S. Chandler, Fitchburg, Mass., assignor to
The Brown Bag Filling Machine Company,
Fitchburg, Mass., a corporation of Massachusetts

Original application October 30, 1936, Serial No.
108,487. Divided and this application January
26, 1939, Serial No. 253,022.

3 Claims. (Cl. 226—49)

This is a division of my co-pending application, Serial No. 108,487, filed October 30, 1936, for Bag filling machine (Patent 2,173,409, issued September 19, 1939).

5 The invention relates to means and arrangements for transferring bags from one conveyer to another, and for conveying the bags to a delivery point and at the same time sealing the bags.

10 It has for an object to effect a simplifying of construction and arrangement of mechanical parts for the purposes indicated and to so coordinate the delivery conveyer with a conveyer of erect bags that a minimum of space and complication in movement of the product is involved in order to effect the desired function.

Another object is to present a novel construction in the delivery conveyer and in its operative means.

15 Additional objects, advantages and features of invention reside in the construction, arrangement and combination of parts involved in the embodiment of the invention as will be understood from the following description and accompanying drawings, wherein

20 Figure 1 is a side elevation of a machine constructed in accordance with my invention.

Figure 2 is a front view of the machine.

25 Figure 3 is a top view with the hopper and measure mechanism removed and partly in section.

Figure 4 is a top view of the operating means for the rotary conveyer.

30 Figure 5 is a fragmentary vertical section on the line 5—5 of Figure 4.

Figure 6 is a detail of one unit of the delivery conveyer on its track-way.

35 Figure 7 is a fragmentary section longitudinally of the path of the delivery conveyer at one sprocket.

Figure 8 is a detail of the ratchet operation for the delivery conveyer.

40 Figure 9 is a fragmentary bottom view of the delivery conveyer.

Figure 10 is a detail elevation of the delivery conveyer.

45 Figure 11 is a detail section of the drive connections.

Figure 12 is a detail section of the drive connections at right angles to Figure 11.

Figure 13 is a detail of the bag.

There is illustrated a bag filling machine which comprises a stand or pedestal 40, having the foot casting 41, and carrying a frame-work 42 which includes a knee bracket 43 and a table 47

5 to which the bracket is attached by the flange arms 46. The frame work also includes up-standing side posts 49 erected on the table, one at each side near the front of the machine and one at the rear, and carrying at their upper parts a platform 50, which serves as the mounting of a hopper 151 and measure mechanism not forming a novel part of the present invention, and therefore not described herein but reference is made to my co-pending application before mentioned for an understanding thereof. The bracket 43, table and platform are arranged one above the other, as may be seen. Over the table there is erected a rotary conveyer 91 having a central vertical main shaft 80 concentric therewith and from which operative connections are made to operate the conveyer step-by-step at proper stages, as will be described.

10 Over the conveyer there is a circular top plate 51 serving as the means for mounting bag working units and fenders. Around the path of the conveyer there is also mounted a retaining rail 205 by which the top portions of bags are held against excessive outward movement, as might be caused by wind or otherwise.

15 There is at the front or filling station A of the machine a bag presenting means 125 operative as will be explained, and a bag-opening means 138 cooperative therewith and with the conveyer. The latter includes a bag-engaging and carrying means 95, constructed to receive the filled bag, including a clamp arm to hold the bag. The measure device 185 is operative to introduce a charge of material through a chute 194 and through the bag opener 138 to the bag when 20 the opener is in opening relation to the bag, the details of which are fully described in my said prior application and also in my later divisional application relating thereto, Ser. No. 253,021, filed January 26, 1939.

25 While this invention is applicable to other forms of bags, in the present instance and in the machine of my prior application the apparatus has been constructed to work with flat open ended bags 200, each of which consists of a front 45 wall 201 and a back wall 202, which is joined to the front wall at the lateral edges and bottom of the bag, the upper or outer edge of the back wall stopping a distance inwardly of the boundary of the front wall and so forming a throat 204, 50 while the material of the front wall is continued therebeyond a distance without creasing and shaped to form the tongue 203 by which the bag is ultimately closed. The bags are arranged in the device 125 with their throats 204 all pre- 55

sented toward the conveyer, their tongues 293 upstanding and at such level that when the opener 138 is elevated it still laps the tongues, but clears the throats 294, and the pressure of the succeeding bags causes the throat of the first bag to be sprung away from the tongue and respective front wall. Consequently, when the opener is lowered it enters between the front and back walls and opens the bag.

10 There is mounted at the left on the under side of the knee bracket a motor 54 which, through belt 55 from its pulley 56 to a pulley 57 on a horizontal shaft 58 at the right hand side beneath the knee bracket, operates the latter shaft but releasably through a clutch. The clutch includes a friction disc 62 fixed on the shaft 58, and the pulley 57 longitudinally slideable on the shaft and pressed against the disc by a lever 71, operated by cam 73 and hand lever 67. By one-to-one worm gearing 74—75 a horizontal countershaft 76 is operated over the shaft 58, this shaft being extended from adjacent the shaft 80 toward the right. Bevel gears 77—78 transmit motion synchronously from the countershaft to the main shaft 80 before mentioned. On the right hand end of the countershaft 76 a cam disc 147 is mounted having a groove 148 therein receiving the wiper 149 of a lever 145 fulcrumed on an arm 146 attached to and depending from the knee bracket 43. The forward end of this lever is connected to a plunger 141 extending vertically through the table 48 and a guide sleeve 142 mounted on the table, having on its upper end a vertically adjustable arm 140 carrying the opener 138 before mentioned, the lever 145 thus constituting the operating means for the opener.

15 The shaft 80 has a horizontal disc cam 106 (Figs. 4-5) mounted thereon under the table 47, formed with the cam groove 107 in its upper side, and at the left of the machine there is pivoted for horizontal motion closely disposed over the disc, a lever 109 carrying the wiper 110 intermittently of the length of the lever and engaged in the groove.

20 The conveyer frame member has a series of pins 88 dependent from its under side and the table 47 has a channel 89 concentric with the shaft 80, in which these pins 88 move freely. In a suitable channel on the under side of the table 47 a bar 112 is mounted reciprocably, this bar having a depending pin 113 engaged in a slot 111 extending longitudinally in the end of the lever 109, so that oscillation of the lever will reciprocate the bar. The bar is provided with a spring 55 pressed latch bar 114 normally tending to swing into the path of the pins 88, but stopped with its end in the path. Consequently, on movement of the bar 112 forwardly, the end of the latch bar 114 will press against one pin 88 and rotate 60 the conveyer until the movement of the bar ceases, and on return movement of the bar the latch bar will be engaged by the next following pin 88 and will yield thereto until its end clears, when it will again move into the path of the pins 65 ready to repeat the step operation of the conveyer on the next movement of the bar.

25 At the same time that the conveyer is operated, the bar also operates the bag presenting device, being extended beyond the pin 113 and provided 70 with strike blocks 136—137 on its under side arranged to engage a strike pin 135 on a lever 134 of the first order pivoted on the under side of the table and connected by a link 133 to the pivot pin 132 on the under side of the bag presenting device 125, so as to operate the latter. The open

25 bags 200 are thus moved inward to position for opening of the first bag as the movement of the conveyer terminates on each step, and after an interval those bags other than the one opened are drawn forwardly and outwardly, releasing the 5 opened and now loaded bag, to drop upon the respective adjacent carrier element of the conveyer.

30 A number of bag working units are located at 10 respective stations, B, C, D, E, around the conveyer path, in succession beyond the filling station A, all according to the movement of the conveyer on each stage or step. These have suitable operative means operated from the shaft 80 to work the bags for various respective purposes during the intermission of motion of the conveyer, all 15 of which are particularly described in my prior application.

35 Finally, at a corresponding distance beyond the station E, a transfer and sealing and delivery conveyer 300 is located at a delivery station F, which 20 is the sixth station shown, although the conveyer has seven steps of movement in each revolution. Some of the bag working stations or devices may be omitted if desired, if their functions are found 25 non-essential, or other working devices substituted. The work at the last station preceding the delivery station results in the closing of the bag with the tongue gummed and turned downwardly 30 against the back wall on a sharp crease formed 35 at the base of the tongue and constituting the top edge of the closed bag, and it is held in the carrier of the conveyer with this thin upper edge portion of the bag set out from the adjacent parts of the conveyer as shown and described in my 40 prior application. Consequently, in the rotation of the conveyer, the filled and closed bag is in erect position, with its upper end set outward and clear from all parts of the conveyor and other apparatus of the machine.

45 In line with the station F and extending radially, there is a special type of conveyer 300, having a novel arrangement in relation to the conveyer 91 and its carriers and serving the double function of removing the bags from the 50 conveyer 91, sealing the bags, moving them to a distance and discharging them. The bag as it leaves the closing station E has its tongue gummed and laid against the back wall of the bag as mentioned, but to remove any possibility that it 55 will spring open before the gum has hardened, as well as to give the bag a good appearance, further pressure of the tongue for a suitable period of time is generally considered essential, and the conveyer 300 is designed to effect this treatment.

55 For the mounting of the conveyer 300, a standard bracket 296 is secured to the side of the table 47, at the upper end of which there is a bearing 298 in which the main shaft 299 of the transfer 60 conveyer is journalled. A bracket 297 is secured to the post 49 at the same side of the machine, this post being near the front of the machine, and on the standard the frame bars 302 of the conveyer 300 are mounted. Owing to the fact 65 that the radius of station F is inclined rearwardly, the bracket 297 is extended outwardly a distance from the machine in order to lie in a line with the standard 296 at right angles to the conveyer frame 302. A drive sprocket 303 of the 70 conveyer is fixed on the shaft 299, and end sprockets 304 at a lower level are revolvably mounted at the outer ends of the frame bars 302. These bars are longitudinally adjustable on the standard, so that the conveyer may be kept taut, and so 75

that the gap in the conveyer at its inner end may be adjusted relatively to the conveyer 91 and the path of bags thereon, as will be understood hereinafter. Side rails 314 are mounted on the standard and bracket 297 at each side of the lower reach of the conveyer 300, upon which this part of this conveyer is supported throughout its length.

The conveyer comprises a link chain 304 comprising blocks 305 and links 306 all of which may be stamped from sheet metal, as shown. The blocks comprise two identical parts L-shaped in section transverse to the chain and consisting of an inner plate 307 forming one-half of a block, to which a similar plate is laid in registry to form the other half of the block. Each plate 307 is apertured at each end to receive link pins 308, and has an outer mounting flange 309 extending at right angles to the plate in a plane parallel to a line from center to center of the apertures in the plate. The flanges thus extend oppositely from each other and are riveted or welded to clamping members to be described. The links comprise a pair of similar plates and flanges but instead of the plate portions being close together, they are spaced to receive the block portions therebetween. The flanges of the link members are also riveted or welded to clamping members coacting with those carried by the blocks, as will be described. The teeth of the sprockets fit between the pins 308 and plates 307 of the blocks.

The clamping members of the conveyer are alternate rigid elements 310 and elastic cushion elements 311. The rigid element consists of a simple rectilinear bar or tube 312 rectilinear in cross section arranged transversely of the chain with a planiform face 312' at the lower side to which are secured one pair of flanges 309 of the chain. The bars may be variously formed but as illustrated may comprise lengths of drawn tube stock. The cross sectional dimension is greater in a direction perpendicular to the planes of the flanges 309. Each cushion element comprises a top plate 313 of hard metal extending parallel to the bars 312, but of greater length so as to project at each side of the conveyer over the parallel rectilinear rails 314, one rail being carried by the bracket 297 and the other by the standard 296. A back wall 315 which may be integral with the plate 313 is extended outwardly from one longitudinal edge of this plate at right angles, on which an outer retaining wall or flange 316 is formed at right angles, making a channel-like space between the plate 313 and flange 316, in which there is secured a block 317 of cushion rubber of the same length as the bar 312, and having a face abutting and compressed by one adjacent bar 312 when the chain is arranged in a rectilinear path. The area of this compressed face of the block may be the same or less than that of the abutting face of the bar, but sufficient to cover an area equal to that of the folded end part of the bag. The thickness of the rubber blocks and the bars is such that when the chain and clamping members are arranged in a rectilinear path the aggregate thickness of all, longitudinally of the conveyer, tends to be greater than the actual length within which they are disposed, so that the rubber is necessarily deformed by compression between the bars. The flange 316 may project from the wall 315 less than the width of the top of the bar 313 and the top of the bar 312 may be arranged below the plate 313. The sprockets 301 are a distance below the level of the drive sprockets 303, so that

the drive sprocket may clear the lower reach of the conveyer. The plates 313 and flanges 316 are narrower than the corresponding faces of the block 317 so that there is no interference with compression of the rubber, and no other element prevents arrangement of the conveyer in a rectilinear path at its lower part with the blocks 317 properly compressed.

The conveyer members 310 and 311 become widely divergent when passing around the sprockets 301 at the ends of the frame, and the operating means for the conveyer moves it step by step so that a gap 321 is formed between two divergent clamping members wherein the rubber face is exposed at one side, positioned over the carrier ring 93 conveniently to receive a bag top moving on the inner table. The means for operating the conveyer includes a link 322 connected to the opener lever 145, extended upwardly beside the standard 296 and connected to a ratchet lever 323 pivoted on the main shaft 299 of the conveyer. Fixed on the shaft 299 beside the lever 323 there is a ratchet wheel 324, the lever being projected beyond the ratchet wheel opposite the link 322 and provided with a spring-pressed dog 325, while on the side of the standard spaced from the full stroke position of the dog there is a spring-pressed pawl 326 to hold the ratchet against reverse movement. To simplify the construction, the ratchet is formed with the same number of teeth as the driving sprocket. In this way, one bar 312 and one block 317 will be moved past the receiving position on each operation of the ratchet.

At the receiving side of the station F, the top guide rail 205 should stop short of the path of the bags in the conveyer. A guide plate 327 on the top plate 51 acts with the rail 205 to confine the advancing bag tops to the path necessary to enter the gap 321 in the open part of the conveyer freely.

The operation of the conveyer to move the two divergent clamp members forming the receiving gap 321 outward until they are pressed together may be coincident with the operation of the opener, and may begin shortly before the index movement of the index table stops, as the advancing bag will have already been entered partly in the gap and actual clamping or material friction will not occur in the early part of the movement of the conveyer. The motion may be otherwise timed, however, as found desirable.

In the operation of the conveyer, it will be noted that the sealed bags are held therein over a period which may be any multiple of the index periods according to the length of the conveyer, and with a comparatively short conveyer, as illustrated, each bag is held clamped therein during two turns of the index carrier of the machine, or fourteen filling operations.

It is also an advantage of this machine that the packages are delivered in an orderly fashion so that they may readily be arranged in cartons or other shipping and sales containers and cases.

Each of the carriers includes a back plate 231, and vertically adjustable rest pins 232 on which the bottom of a bag may rest while pressed against the plate 231, and a spring-pressed gripper lever 234 having an upwardly extending arm adapted to and normally pressed inward and tending to clamp the lower part of a bar against the plate 231. The arm has knobs 235 to engage the bag very close to the lower edge, so that the upper end of the bag is caused to set outward from the plate 231. The lever is also provided with a de-

pending arm 236 by which it may be operated to release and receive bags. The cam rail 238 is mounted over the table 47 in position and so shaped as to engage the arm 236 when the carrier enters the station F, and hold it open until it departs from station A.

Operation

The operation, as will be understood, is as follows: Bags are presented and filled at station A, and each one progresses with the conveyer movement through the several stations and finally leaves the closing station to move into station F, with its tongue pressed down against the back 15 wall of the bag.

Here the conveyer 300 stands with a gap 342 therein located over the path of the carrier 95, and by means of the top guide 205 the advancing corner of the bag is pressed inwardly so that it 20 enters the gap properly, this guide rail being located below the anvil of the folder; and an opposed fender plate 343 may be provided on the top plate 51 by which the bag top is properly held outward from the carrier 95. The index 25 operation then brings the bag with its trailing vertical corner well within the side boundary of the conveyer, and the next operation of the opener lever 145 moves the conveyer one step, closing the gap, pressing the cemented parts of the bag 30 top firmly between the members 310 and 311, and moving the bag radially from the carrier so as to clear the path of the following bag. The bag is held compressed in the conveyer and suspended therefrom throughout a number of succeeding 35 step movements of the index carrier and conveyer, and finally, when the part of the conveyer holding the bag reaches the outer sprocket 301, the clamping members open by assuming radial positions on the sprocket and release the bag. The bag then falls by gravity, and may be caught, collected, or ordered and packed or cased by any 40 suitable means, not shown.

I claim:

1. In a machine of the class described capable 45 of measuring stock, feeding empty bags to a filling station and filling them, and having means to advance them edgewise in erect position and closing and delivering the completed packages, the combination of a first conveyer adapted to receive 50 and hold loaded bags in erect position in a plane coincident with direction of movement of the bags and to advance the bags edgewise in erect position, means to operate the conveyer step-by-step, a delivery conveyer consisting of an endless member having clamp elements on its outer side 55 constructed to abut continuously but separably at a distance from the endless member when the latter is moved in a straight path and to diverge when the endless member is moved in an arc of moderate radius, said delivery conveyer being 60 mounted for circuitous movement with a straight departure path at its lower side extending from closely adjacent the path of the first conveyer and above the level of the bag tops on the latter,

and having a curved path of short radius immediately over and adjacent the first conveyer, said clamp elements movable with the delivery conveyer intermittently and alternately with the motion of the first conveyer, and means to move the delivery conveyer intermittently and alternately with the motion of the first conveyer, the delivery conveyer and the means to move the same being constructed so that its clamp members next the first conveyer will be positioned divergently in said curved path with the opening between two aligned with the path of the bags at each intermission of its movement, said delivery conveyer being mounted with an outer curved path also, whereby to cause release of gripped bags.

2. In a machine of the character described, the combination, construction and arrangement of means to advance flat bags step-by-step edgewise in erect position with a flap having adhesive thereunder at the top, an endless conveyer chain device arranged to move in a vertical orbit extending at right angles to and partly across the path of the advancing bags, and comprising complementary clamping elements on respective link elements of the chain, said conveyer having a rectilinear reach at its lower part positioned at a level with the tops of the advancing bags, and having a supporting wheel at the inner end of said reach adjacent the first named path of the bags and another at the end of said reach, whereby said complementary members will be held in a widely separated position immediately at the first named path, and means to operate the chain conveyer intermittently and during periods of rest of the bag advancing means, whereby opened complementary members will be stationary and located at opposite sides of an edgewise advancing bag, and will be moved into the horizontal reach in clamping relation to an interposed bag during the succeeding period of rest of said bag advancing means, carrying the last engaged bag, and will release the same at the outer end of the reach.

3. In a conveyer of the character described, a primary conveyer movable in a fixed path, and constructed to move articles with a free portion projected in one direction, a second conveyer arranged to move in a path transverse to that of the first conveyer, and consisting of pivoted clamp members pivoted in a chain relation and having major parts outwardly of the pivotal connections in the direction of the first conveyer, guide means for the second conveyer adjacent the first conveyer to cause it to move in a curved path and to support the clamp members in divergent relation to their said projected parts while crossing the path of the first conveyer, and means to move the two conveyers step by step alternately and to position the second conveyer with divergent clamp members spaced at opposite sides of the path of the said free portion of the articles on the first conveyer during intermission of movement of the latter.

AUSTIN S. CHANDLER.
